ARC LAMP MECHANISM

Clarence T. Crocker, Daytona Beach, Fla., assignor to General Electric Company, a corporation of New York

Application December 22, 1939, Serial No. 310,597

7 Claims. (Cl. 176—66)

My invention relates to arc lamp mechanisms, and more particularly to electrode feeding mechanisms for high powered arc lamps such as are applicable for searchlight use.

One object of my invention is the provision of an improved mechanism for feeding an electrode at rates variable in proportion to the fluctuations in predetermined arc characteristics.

Another object of my invention is to minimize the mechanical load on the regulating magnet of an electrode feeding mechanism to increase its sensitivity.

For a better understanding of my invention, together with other and further objects thereof, reference is had to the following description taken in connection with the accompanying drawings, and its scope will be pointed out in the appended claims.

In the accompanying drawings, Fig. 1 is a side elevation, partly diagrammatic, of a conventional arc lamp mechanism provided with a control mechanism built in accordance with my invention; Fig. 2 is a perspective view of the control mechanism of Fig. 1 including all its control elements with the interconnecting shafts elongated so that each element may be viewed in its relation to the other elements of the mechanism; Fig. 3 is an enlarged perspective view of a group of elements illustrated in Fig. 2; and Fig. 4 is an enlarged side view of a part of the mechanism illustrated in Fig. 3.

Referring to the drawings in detail, Fig. 1 illustrates, diagrammatically, a conventional electrode feeding mechanism for feeding both of the electrodes of an arc lamp, automatically or manually, independently of each other. The negative electrode 10 is supported on two pairs of rollers 11—11' and 12—12', of which rollers 12—12' are actuated to feed the electrode. These rollers are mounted on shafts 13—13', respectively, having interengaging gears 14 and 14' mounted on their ends. These gears are in turn driven by a worm 15, engaging the gear 14, and mounted on a shaft 16. Shaft 16 is driven through beveled gears 17 and 17', the latter of which two gears is mounted on a shaft 18. The mechanism for driving shaft 18 is mounted in a box 19 and is shown in detail in Figs. 2, 3, and 4.

Still referring to Fig. 1, a positive electrode 20 is supported, for rotation about its own axis and for axial movement, within a cage 21. This cage 21 is a U-shaped member supported at its closed end by a hollow shaft 22 which is coaxial with the positive carbon. This cage and shaft are rotated by a mechanism including a bevel gear 23

5 mounted on the end of the shaft 22, a bevel gear 24, mounted on a shaft 25, bevel gears 26 and 26' and a shaft 27. The mechanism for driving the shaft 27 is enclosed in the box 19 and is shown in detail in Figs. 2, 3, and 4.

The positive electrode 20, as illustrated in Fig. 1, is supported within the cage 21 by a pair of feed rollers 30—30' which are rotated to axially advance, or feed, the carbon. The feed rollers are mounted on shafts 31 and 32, respectively. The shafts 31 and 32 are supported in the sides of the cage 21 and are connected by interengaging gears 33 and 34 mounted on the shafts. They are driven by a system of gears including a gear 35 mounted on the shaft 31, a gear 36 engaging gear 35 and mounted on a shaft 37, a gear 38 also mounted on the shaft 37, and by a worm 39 which engages gear 38. The worm 39 is mounted on a shaft 40 projecting through the end wall 20 of the cage 21, upon the other end of which a gear 41 is mounted. Gear 41 engages a gear 42 which is rotatable on the hollow shaft 22 and is connected by pins 43 to a cam 44. When the shaft 22 is rotated, the cage 21 and the described system of shafts and gears move with it, and no axial movement of the positive electrode 20 takes place. If, however, during the movement of shaft 22 the cam 44 is held stationary, the gear 42 remains stationary and gear 41 rolls about 25 the axis of gear 42. The entire train of gears between the cam 44 and the feed rollers 30—30' is thereby set into motion and a forward movement of the electrode 20 takes place.

For the purpose of holding the cam 44 stationary, the cam 44 is built in the form of a ratchet wheel, and a pawl 45 is mounted on a shaft 46 for cooperation with this wheel. Normally this pawl is held in a position parallel to the cam 44. When it is desired to hold the cam 44 stationary, this pawl 45 is moved about the axis of the shaft 46 over an arc of 90°, into the path of movement of the ratchet teeth. The cam moves until the face of a tooth engages the pawl 45, and then remains stationary as long as 45 the pawl is held in this second position. The pawl shaft 46 is moved by bevel gears 47—47' and a shaft 48. The mechanism for moving the shaft 48 is also enclosed in the box 19.

At the side of the box 19, two cranks 50 and 51 50 are shown. These are provided for the manual operation of the shafts 18 and 27, respectively. A knob 52 is provided and positioned between the two cranks for adjusting the linkage mechanism which actuates the shaft 48 and the pawl 45.

Fig. 2 illustrates in an expanded perspective

view the operating mechanism enclosed in the box 19 of Fig. 1. The shafts interconnecting the respective gears are elongated for the purpose of more clearly illustrating the interconnection between the gears and the other elements which perform the several functions of the mechanism. The prime mover for the mechanism is a motor 53. This motor drives the shaft 27 of the positive electrode rotating mechanism, through a worm 54, interengaging gear 55, shaft 55, gears 57-58, shaft 59, and bevel gears 60-60' of which gear 60' is mounted on the shaft 27.

The shaft 27, as above stated, may also be rotated manually by the crank 51. This crank is mounted upon a shaft 61, upon which one jaw 62 of a coupling is mounted. The second jaw 63 of this coupling is mounted on a shaft 64 which is connected to the shaft 27 through bevel gears 65-65'. The jaws 62-63 of the coupling are normally held in disengaged position by a spring 66. The crank 51 and shaft 61 may be moved axially against the pressure of this spring to bring into engagement the two jaws 62-63 of the coupling. The coupling will transmit torque only in one direction; that is, in the direction of normal rotation of the electrode, and in this direction the shaft 27 may be moved ahead of the movement imparted by the motor 53. For this purpose, a ball clutch is provided between the gear 58 and the shaft 59. This is merely a standard form of ball clutch in which balls 67 roll into notches in the hub 68 of the gear 58 to release the shaft and permit relative movement between the shaft 59 and the gear 58 when the shaft 59 is moved ahead of the gear. When the gear 60 is first rotated, however, a slight movement between the gear and shaft 59 causes the balls 67 to wedge between the shaft 59 and the gear hub 68, and the shaft is thereafter rotated with the gear.

The feeding mechanism for the positive electrode may be actuated automatically at regular intervals, manually at any desired interval, and automatically in response to a condition of the electrode, such as, for example, a change in the length thereof and the resulting change in the position of the electrode tip. The regular intermittent movement is imparted thereto by an actuation of the pawl 45 through a cam 71 mounted on the shaft 27 and a cooperating actuating mechanism. This actuating mechanism for the pawl 45 includes a roller 72 mounted on a lever 73 which is pivoted between its ends upon a pin 74. The lever 73 actuates a link shaft 75 upon which an adjustable nut 76 is mounted and connected to a lever 77. The lever 77 is pivoted near its center upon a pin 78, and through a pin connection 79 is connected to a link 80. The link 80 is connected to one end of a crank 81 which is mounted upon the shaft 48 (see Fig. 1). A rotation of the cam 71 effects a rotation of the shaft 48 through the mechanism just described to cause the pawl 45 to move into the path of the cam 43 once during each revolution of the shaft 27.

An additional movement of the electrode may be superposed by the manual rotation of the crank 51, which by rotation of the shaft 27 increases the speed of rotation of the cage 21, and simultaneously increases the frequency of operation of the pawl 45 to effect a greater speed of forward movement of the electrode 20.

The knob 52, mounted on the side of the control box, is operable to adjust the linkage between the cam 71 and the shaft 48. The knob

52 is mounted upon a shaft 82, and is connected to the threaded shaft 75 through a sleeve 83, mounted on the shaft 82, and a pin 84 mounted on the shaft 75. The sleeve is provided with 5 slots 85 to receive the pin 84 and thereby form a pin and slot connection between these two shafts. The lever 73 is connected to the shaft 75 by engaging the sides of a nut 86, the lever 73 being bifurcated at its end for this purpose. 10 The ends of the lever 73 are held in a channel formed by flanges 87 projecting from one side of the nut and engaging one side of the lever ends, and a plate 88 loosely mounted on the shaft 75 engaging the other side of the nut and of the lever ends. The plate 88 is held against the lever ends by a spring 89 which is under compression between the nut 76 and the plate 88. A turning movement of the knob 52 rotates the shaft 75 and opposite threads on the shaft regulate the distance between the nuts 86 and 76 and thereby adjust the linkage mechanism.

The pawl shaft 48 may also be moved by the energization of a magnet 90 which attracts its armature 91, pivoted upon pin 92. The armature is connected to the shaft 48 through a linkage mechanism including link 93, lever 94 pivoted near its center on pin 95 and connected to the shaft 80 by a pin 96 and slots 97 in the end of the bifurcated end of the lever 94. The circuits for energizing the magnet 90 are not illustrated in this diagram. There are now many devices in use for feeding the positive electrode to maintain its tip in a predetermined position, one such device being described in United States Patent 1,313,666, issued August 19, 1919, to Beck. The magnet 90 may be energized in response to any one of such devices.

It is necessary to move the negative electrode axially to strike the arc and also to regulate the 40 intensity of the arc during operation. It is desirable, therefore, to provide a mechanism which is sensitive to a condition of the arc and which will effect a movement of the electrode to establish and maintain this desired condition of the arc.

The mechanism, built in accordance with my invention, for feeding the negative electrode, as illustrated in Fig. 2, includes the motor 53, worm 54, gear 55, and the shaft 56 of the positive electrode mechanism. To drive the negative electrode mechanism, a gear 100 is mounted on the shaft 56. This gear 100 engages a gear 101 mounted on a shaft 102. The shaft 102 carries two gears 103 and 104 which are loosely 55 mounted thereon and are alternately connected to the shaft by a pawl and ratchet mechanism actuated in response to an arc characteristic or condition, such as, for example, the voltage across the arc or the current through the arc. 60 The gear 103 engages a gear 105 on a shaft 106 and drives this latter shaft in a clockwise direction when connected to the shaft 102. The gear 104 engages a pinion 107 which in turn engages a gear 108 also mounted on the shaft 106, and thereby drives the shaft 106 in a counter-clockwise direction when it is connected to the shaft 102. The gear 109 mounted on the end of the shaft 105 drives the negative electrode feeding shaft 18 (see Fig. 1) through a 65 gear 110 mounted on a shaft 111 and by a pair of bevel gears 112 and 112', the first of which is mounted on the shaft 111, and the second of which is mounted upon the shaft 18.

This shaft 18 may also be driven, manually, by the crank 50. This crank 50 is mounted upon

a shaft 113 rotatably mounted in a disk 114. The disk 114 is spaced from the gear 110 by rods 115 and 116. The gear 110 is slidably mounted upon the shaft 111 and is normally held in position to engage the gear 109, by a spring 117. When it is desired to operate the shaft 18 manually, the crank 50 with shaft 113 and disk 114 is moved axially of the shaft 111, the shaft 113 being provided for this purpose with a sleeve 118 which slides over the end of the shaft 111. This movement disengages the gear 110 from the gear 109 and places prongs 119 and 120, attached to the disk 114, in engagement with a disk 121. This disk 121 is rigidly mounted upon the shaft 111 and is provided with notches 122 to receive the prongs 119 and 120. When the gear 110 is out of engagement with gear 109 and the prongs 119 and 120 are in the notches 122 of the disk 121, the shaft 18 may be turned in either direction by correspondingly turning the crank 50 in either direction.

The ratchet and pawl mechanism which alternately connects the gears 103 and 104 to the shaft 102 for driving the negative electrode shaft 18 may be described by reference to Figs. 2, 3, and 4. Referring to Fig. 2, the gears 103 and 104 are respectively coaxially connected to ratchet wheels 125 and 126, and may be connected to rotate with the shaft 102, respectively, by pawls 127 and 128 carried by a member 129 rigidly mounted on the shaft 102 between the ratchet wheels 125 and 126. The pawls are respectively provided with a forward, or nose element 130-131 and a back end, or tail, element 132-133 (see also Fig. 4), and are pivotally mounted upon shafts 134 and 135, respectively. The nose and tail elements of each pawl are spaced transversely of each other so that, as the pawls are moved by the shaft 102 in a circular path, their respective nose or tail elements may be respectively engaged by transversely movable rollers 136 and 137 mounted respectively upon arms 138 and 139 of a pivoted bifurcated relay member 140. This relay member is mounted upon a pivot pin 141 and is counter balanced by a weight 142 mounted upon an arm 143. It is moved through a limited arc, so as to move the rollers 136 and 137 transversely with respect to the motion of the pawls 127 and 128, by an armature 144 operable between field poles 145 and 146, these poles being excited by a relay coil 147 wound upon a core member 148 connected between the field poles. The movement of the armature 144 is responsive to the excitation of the field poles 145 and 146 which tend to move the armature counter-clockwise against the tension of springs 149 and 150, the springs being adjustable and the excitation of the field poles being proportional to the current flowing in the coil 147.

In operation, the coil 147 may be connected to carry current responsive to the potential across the arc, or responsive to the current flowing through the arc, and thereby move the armature 144 relatively to the poles 145 and 146. In the illustrated example, relay coil 147 is designed to carry the full arc current. In normal position, the rollers are positioned opposite to the tail sections 132 and 133. The pawls are, in this position, forced out of engagement with the ratchet wheels. The armature 144 is held in this position by the balanced pull of the field poles and the springs 149 and 150. A slight transverse movement in either direction, however, will bring a roller into engagement with the nose section

of a pawl to effect an engagement of the pawl with the ratchet wheel. If the current increases in the coil 147, for example, the field will overcome the pull of the springs 149, 150 and the armature 144 will rotate counterclockwise to carry roller 136 into the plane of movement of the nose member 130 of the pawl 127. When the nose member is moved past the roller 136 the nose member is forced forward to move the pawl about its pivot to engage the pawl with the ratchet wheel 125 as illustrated in Fig. 3. In this manner, the shaft 102 drives gear 103, and thereby drives the shaft 18 to move the negative electrode axially. This specific engagement of the pawl and ratchet holds until the roller returns to its position opposite the tail member 132. The pawls are so arranged that the nose is normally opposite to the roller prior to the tail member in each revolution. Therefore, if the pawl nose is moved into engagement with the ratchet wheel, and a slight correction of the electrode will restore normal arc current, the roller will be returned to normal position, and thereby will disengage, or release, the pawl from its ratchet wheel in a fraction of a revolution of the ratchet wheel. If this slight movement of the gear 103 is not sufficient to retract the electrode to a position at which the arc current is normal, the gear 103 will continue to rotate with the shaft 102 until such normal condition is reached. The armature will then move the rollers to the intermediate position, and roller 136 will engage the tail 132 to raise the nose 130 out of its notch on the ratchet wheel to release the gear 103 and thereby stop the axial movement of the electrode.

If the arc current is too low, the pull of springs 149-150 will overcome the pull of the field magnet to move the rollers clockwise. In that case, roller 137 will be moved into position to engage nose 131 of the pawl 128 and will cause it to engage ratchet wheel 126 to move the shaft 106 counter-clockwise and thereby advance the negative electrode 10. If the advance of the electrode is sufficient, within the fraction of the revolution between the nose 131 and the tail 133, the field will move the roller back to normal position and roller 137 will engage the tail 133 to release the gear 104 and thereby again stop the electrode feed mechanism. If the correction required is greater, then the gear 104 will continue to drive the shaft 102 for one or more revolutions until such correction is made.

The roller carrying relay arm which initiates and stops the feed mechanism through operation of the pawls is free to move about its axis on pivot pin 141, responsive to the pull of armature 144 and of the springs 149-150. The energy required to engage and disengage the pawls is provided by the prime mover motor 53 above, and there is, therefore, no mechanical load placed on the relay to reduce its sensitivity. The width of the rollers 136 and 137 and their respective positions relatively to the pawls are chosen to give a desired sensitivity.

The pawls are provided with an interlock device which permits only one pawl at a time to move into driving engagement. This is illustrated clearly in Fig. 4. This interlock consists of an interlock bar 151 loosely mounted in the member 129 and projecting outwardly to engage bars 152 and 153 projecting from the pawls 127 and 128, respectively. The length of the bar 151 is such that the movement of one pawl into engagement with its ratchet wheel forces the

other pawl out of engagement with its ratchet wheel.

The pawls 127 and 128 are further moved into and out of operation with a snap action. This is imparted by an over-center device. The pawl 127 is pivoted upon shaft 134 by a sleeve 154. The pawl is attached to one end of the sleeve and a cam 155 is attached to the other end of this sleeve. The cam 155 is provided with an end surface having a high point at its center. A ball 156 urged forward by a spring 157 engages the end surface of the cam and urges the cam and pawl to an end position on either side of this high point in the end surface. The pawl 128 is similarly mounted on a sleeve 158, the pawl being attached to one end of this sleeve and a cam 159 being attached to the other end. The cam 159 is urged to either of its end positions by a ball 160 urged forward by a spring 161. The springs 157 and 161 are suitably mounted in the block 129.

The gears 103 and 104 are connected to the ratchet wheels 125—126 through resilient connections so as to reduce the shock produced when a pawl engages the rapidly moving ratchet wheel. In Fig. 3, the gear 104, together with its hub and ratchet wheel 126 is illustrated in section. The ratchet wheel 126 is directly attached to a hub member 162. The gear 104 is slidably mounted on the hub 162 between a flange 163 and a disk 164 attached to the end of the hub. A spiral spring 165 is wound about the gear hub. It is attached at one end to a pin 166 in the disk 164 and at the other end it is attached to a pin 167 on the gear 104. Normally the spring which holds the gear 104 at one end of its range of movement is determined by a pin 168 in the gear 104 projecting into a slot 169 in the flange 163 on the hub 162. When the pawl 128 engages the ratchet wheel 126, the hub 162 is suddenly moved ahead of the gear and an additional tension is placed upon the spring 165. The gear follows the pawl due to the tension on the spring and moves back to its initial position without noticeable shock to the mechanism.

Fig. 4 is a full side view of the block 129 with the pawls 127 and 128. The pawl 127 is pivoted, with its sleeve 154, on the shaft 134 which is mounted in an ear 170 projecting from one corner of the rectangular block 129. The positioning cam 155 is mounted on the sleeve 154 and cooperates with the ball 156 to hold the pawl 127 in one or the other of its two positions. The ball 156 is pressed outwardly by the spring 157 to present part of its face to the end of the cam 155. The cam surface has two flat faces at an angle to each other with a high point between them. On either side of this high point, the cam is moved to the extreme position of the pawl. A similar cam 159 is connected to the pawl 128 by the sleeve 158. The shaft 135 for this pawl is mounted in an ear 171 projecting from an opposite corner of the block 129. This pawl is similarly held in one or the other of its two positions by a ball 160 urged forward by a spring 161 against the end surfaces of the cam 159.

What I claim as new and desire to secure by Letters Patent in the United States is:

1. In an arc lamp mechanism the combination of a drive shaft, an electrode feeding mechanism, a pawl mechanism attached to said drive shaft to rotate therewith, a ratchet wheel loosely mounted upon said shaft and connected to said electrode feeding mechanism, a pawl actuating relay member pivotally mounted to move transversely of

said rotating pawl in response to variations in an arc condition, and means upon said pawl cooperating with said relay arm to effect a movement of said pawl into and out of engagement with said ratchet wheel responsive to the positioning of said pawl actuating relay member.

2. In an arc lamp mechanism the combination of a drive shaft, an electrode feeding mechanism, a pawl mounted upon said shaft for movement therewith and provided with an engaging element and a releasing element spaced transversely of each other, a ratchet wheel loosely mounted on said shaft and connected to said electrode feeding mechanism, a relay member operable transversely of said pawl in response to variations in an arc condition, and in cooperating relationship with said engaging and releasing elements on said pawl to effect operation of said feeding mechanism.

3. In an arc lamp, the combination of a pair of electrodes, means for moving one of said electrodes relatively to the other of said electrodes to establish an arc therebetween, a relay coil responsive to a condition of said arc, a relay member actuated by said relay coil, a drive shaft, a pawl mechanism rotatable with said drive shaft, a ratchet wheel loosely mounted upon said drive shaft and operable with said drive shaft when engaged by said pawl mechanism to actuate said electrode moving means, and means upon said pawl mechanism cooperating with said relay arm to effect a movement of said pawl into and out of engagement responsive to the position of said relay member.

4. In an arc lamp mechanism the combination of a drive shaft, an electrode feed mechanism, a pawl mounted upon said shaft for movement therewith, a ratchet wheel loosely mounted on said shaft and connected to said electrode feed mechanism, a relay member operable transversely of said pawl in response to variations in an arc condition, and means upon said pawl including an engaging member and a releasing member spaced transversely of each other and cooperating with said relay member to effect engagement and release between said pawl and said ratchet wheel in accordance with the positioning of said relay member in response to said arc condition.

5. In an arc lamp, the combination of a pair of electrodes, an actuating mechanism for one of said electrodes comprising feed rolls, a relay coil energized in response to a condition of the arc between said electrodes, a relay member provided with a pair of actuating members pivotally mounted and rotatable responsive to the energization of said relay coil, a drive shaft, a pair of pawls mounted upon said shaft to rotate with said drive shaft, a pair of ratchet wheels loosely mounted upon said drive shaft and operable when engaged by said pawls respectively to rotate with said shaft, means upon said pawls cooperating with said relay member to engage or release said ratchet wheels in response to the positioning of said relay member, and means between said ratchet wheels and said electrode feed rolls to drive said rolls in either of two opposite directions.

6. In an arc lamp mechanism the combination of a pair of electrodes, an actuating mechanism for one of said electrodes, a relay coil energized in response to a condition of the arc between said electrodes, a relay member provided with a pair of actuating members pivotally mounted and rotatable responsive to the energization of said relay coil, a drive shaft, a pair of pawls mounted upon said

drive shaft to rotate with said drive shaft, a pair of ratchet wheels loosely mounted upon said drive shaft and connected to said feed mechanism, one of said ratchet wheels being connected to advance said electrode and the other of said wheels being connected to retract said electrode, means upon said pawls respectively cooperating with said actuating members to effect an engagement or a release of said ratchet wheel in response to the positioning of said actuating member transversely of said pawl, and interlocking means between said pawls to permit an engagement between only one of said ratchet wheels and one pawl at a time.

7. In an arc lamp electrode feeding mechanism the combination of electrode feed rolls, a drive

5 shaft, a pawl mechanism attached to said drive shaft to rotate therewith, a ratchet wheel and gear loosely mounted on said drive shaft and connected to operate said feed rolls, a relay member pivotally mounted to move into and out of the path of movement of said pawl, means for moving said relay member about its pivot in response to variations in an arc characteristic, and means upon said pawl cooperating with said relay member to effect a movement of said pawl into engagement and out of engagement with said ratchet wheel respectively responsive to the operating position of said relay member thereby to effect an operation of said electrode feeding rolls.
